UNITED STATES PATENT OFFICE.

CLARENCE E. GILCHRIST, OF TOLEDO, OHIO, ASSIGNOR TO ELECTRIC AUTO-LITE CORPORATION, OF TOLEDO, OHIO, A CORPORATION OF DELAWARE.

LAMP.

Application filed August 11, 1919. Serial No. 316,726.

To all whom it may concern:

Be it known that I, CLARENCE F. GILCHRIST, a citizen of the United States, residing at Toledo, in the county of Lucas and 5 State of Ohio, have invented certain new and useful Improvements in Lamps, of which I declare the following to be a full, clear, and exact description.

This invention relates to lamps, particularly to those adapted for use as headlights, sidelights and spotlights for vehicles.

An object of the invention is to provide a lamp of this character whose structure shall be simple, strong, dust and water tight, shall 15 present a pleasing appearance and shall be such that its parts will not rattle or become loose when the lamp is mounted upon a vehicle subject to severe vibrations.

A further object is the provision in such 20 a lamp of means whereby the lens covering the front of the lamp may be readily removed to give access to the reflector and to the lamp forming the source of light.

Further objects of this invention relate to 25 economies of manufacture and details of construction as will hereinafter appear from the detailed description to follow. I accomplish the objects of my invention in certain instances by the devices and means described 30 in the following specification, but it is evident that the same may be varied widely without departing from the scope of the invention, as pointed out in the appended claims. Structures constituting certain embodiments of my invention, any one of which 35 may be the preferred, are illustrated in the accompanying drawings forming a part hereof, in which:

Figure I is a front view of the lamp, comprising the invention.

Fig. II is a cross sectional view of the same taken on the line II—II of Fig. I.

Fig. III is a fragmentary cross sectional view on an enlarged scale, taken on the line 45 III—III of Fig. I.

Fig. IV is a front view similar to Fig. I of a modified form.

Fig. V is a cross sectional view taken on the line V—V of Fig. IV.

Fig. VI is a fragmentary cross sectional view on an enlarged scale, taken on the line 50 VI—VI of Fig. IV.

Fig. VII is an enlarged detail view of the connector tube.

In the drawings, similar reference numerals refer to similar parts throughout the several views, and the sectional views are taken looking in the direction of the arrows at the ends of the section lines.

A casing or body portion 4 shown as paraboloidal in form and supported by brackets 5 has a cylindrical portion 6 at its mouth. Within and secured to this cylindrical portion is a ring 7 having an inwardly extending radial flange 8, against which rests a reflector 9 shown also of paraboloidal form. The reflector 9 has an outwardly extending radial flange 10 adapted to overlap the flange 8 of the ring 7, and between these two flanges is a ring 11 of suitable packing material for the purpose of preventing the entrance of dust, dirt and water. This ring 11 may for convenience be permanently attached to the flange 8. The casing 4 and the reflector 9 are each provided with a circular aperture at their central portions for receiving a tubular connector 12 having at one end a flange 13 adapted to engage the front surface of the reflector and at the other end a ring 14 threaded thereon and adapted to engage the outer surface of the casing 4. By means of this arrangement the reflector is detachably secured to the casing, and by turning up the threaded ring 14 may be firmly held against the packing 11. The connector 12 constitutes an outer casing of a focusing lamp socket 18 one end of which is adapted to receive an incandescent electric lamp 16, while the opposite end carries the focusing screw 17. A suitable lead 19 extends from a plug socket 20 mounted in the casing 4 to the focusing lamp socket 18 and a second lead 21 extends from the plug socket 20 to an auxiliary lamp socket 22 mounted in the reflector and carrying an auxiliary lamp 23.

A lens 25 covers the opening or mouth of the reflector and is held in position by a detachable lens ring 26, suitable rings 27 and 28 of packing material being employed respectively between the reflector and the lens and between the lens and the lens ring. The lens ring 26 is constructed of two separate rings 30 and 31 soldered, brazed or otherwise suitably fastened together. The innermost ring 30 is of circular conformation so as to snugly fit over the cylindrical part 6 of the casing 4. The outer ring 31

is shown as having an irregular contour of the shape illustrated by Fig. I.

The lens ring, according to this invention, is secured to the housing by means of a pair 6 of bolts or screws 34. Referring to Fig. III it will be seen that the ring 7 is provided in its flange portion 8 with a nut 33, a similar nut being located on the opposite side of the lamp, which nut is adapted to receive 10 the securing screw or bolt 34 shown in this case as having a hexagon head. This nut 33 is constructed with a portion 35 of reduced diameter which in assembling the apparatus is placed in a suitable opening in 15 the flange 8 and afterward headed or spun over to firmly secure the nut in place and against rotation. The screw 34 is given a pointed end to facilitate its entrance into the nut and adjacent the head is constructed 20 with a portion 36 of reduced diameter. The outer ring 31 is provided with a threaded opening to receive the screw 34 or if preferred, a plain opening may be made, large enough to pass the threaded portion of the 25 screw and after the screw has been inserted, may be partially closed to prevent removal of the screw. By the above described arrangement it will be seen that the lens ring is attached to the casing by the simple expedient of two screws, which when tightened 30 clamp the casing, the reflector, the lens and the lens ring firmly together and when loosened and the ring removed are retained by the ring. When it is desired to replace 35 a broken lens or to renew a lamp globe the two screws 34 are loosened, and the lens ring is slipped off the casing the screws being retained by the ring to avoid loss. Suitable openings 38 and 39 are provided in 40 the lens ring to permit the draining of any water that may find its way into the casing.

According to the modification illustrated by Figs. IV, V and VI, the casing 4', the reflector 9' and the securing means 12' 45 therefor are identical with the corresponding parts of the structure just described. In this case, however, the lens ring comprises a single member 40 having one portion 41 adapted to snugly fit the casing 4' and having another portion 42 extending radially inward, of substantially circular outline and holding the lens 25' in proper position against the reflector and casing. In this modification four countersunk screws 44 are 50 employed which screws engage four nuts 55

33' similar in all respects to the nuts 33 of the previously described form.

Having thus described my invention, what I claim as new and desire to secure by Letters Patent, is:

1. In a device of the class described, the combination of a casing, a nut secured thereto, a reflector within said casing, a lens, a lens ring, a screw carried by said lens ring and adapted to be threaded into said nut 60 to thereby clamp said reflector, lens and lens ring to said casing, said screw having a portion adjacent its head of reduced diameter and said lens ring having an opening for said screw of less diameter than the threaded portion thereof.

2. In a device of the class described, the combination of a casing, a ring having a radial flange secured to said casing, a plurality of nuts fastened to the flange of said 75 ring, a reflector in said casing having a radial flange, packing between said flanges, a lens, a lens ring, packing on either side of said lens, a plurality of screws for clamping said members in assembled position 80 having threaded portions engaging said nuts and having portions of reduced diameter adjacent their heads, the lens ring having openings for said screws of less diameter than their threaded portions.

3. In a device of the class described, the combination of a casing, a reflector therein having a flange for engaging said casing, means comprising a tubular member arranged centrally of said reflector for holding the same in engagement with said casing, a lens overlying said reflector, a lens ring therefor and screw threaded means engaging said lens ring and casing for clamping said lens ring, lens, reflector and casing 85 firmly together.

4. In a device of the class described, the combination of a casing having an inwardly extending flange adjacent its mouth, a reflector having an outwardly extending 100 flange overlapping said first flange, screw threaded means at said flanges to bind the same together, a tubular member for connecting said casing and said reflector at their central portions, a light bulb socket carried by said tubular member for moving said light bulb socket for focusing purposes.

In testimony whereof, I affix my signature.

CLARENCE F. GILCHRIST.
